Primary Examiner—Dominic Simone*Assistant Examiner*—Rashids C. McCoy(74) Attorney, Agent, or Firm—Ganzlaw, P.C.(57) CLAIM

The ornamental design for dance footwear, as shown and described.

DESCRIPTION

FIG. 1 is a front, side perspective view-of dance footwear showing our new design, in use condition;

FIG. 2 is a front, side perspective view opposite to FIG. 1, in use condition;

FIG. 3 -an enlarged front, side perspective view;

FIG. 4 is a side elevational view;

FIG. 5 is a side elevational view opposite to FIG. 4;

FIG. 6 is a front, elevational view;

FIG. 7 is a rear, elevational view;

FIG. 8 is a top view; and,

FIG. 9 is a bottom view.

Broken lines showing features of the shoe, and any showing of a wearer's foot and leg, are for illustrative purposes only and form no part of the claimed design.
